MELVIN D. BALDWIN, ARMEN S. KURKJIAN, AND THOMAS R. RENWICK, OF GRAND RAPIDS, MICHIGAN, ASSIGNEES TO OLIVER MACHINERY COMPANY, OF GRAND RAPIDS, MICHIGAN, A CORPORATION OF MICHIGAN

MORTISING MACHINE

Application filed November 5, 1928. Serial No. 317,216.

This invention relates to a mortising machine for cutting mortises in wood, and is particularly concerned with a machine wherein a great variety of types of mortises can be cut either in a straight line or in a curved line at different elevations and of different depths. In fact the machine is one which is substantially universal in its ability to cut mortises of any desired type or character.

The embodiment of the invention which we have made is illustrated as cutting mortises in curved bars such as are used in the manufacture of automobile bodies, wherein it is necessary that the mortises receiving tenons at the ends of cross slats shall be cut in the arc of a circle or in the arc of the curve of the side members between which connecting cross slats are located. It is, however, to be understood that the machine is not limited in its use and operation to any one type of work.

An understanding of the invention may be had from the following description taken in connection with the accompanying drawings, in which,

Fig. 1 is a perspective view illustrating the curved member of wood in which mortises may be cut on the machine of our invention.

Fig. 2 is a side elevation of the mortising machine.

Fig. 3 is a fragmentary enlarged side elevation and longitudinal vertical section, the plane of the section being taken within one side of the machine.

Fig. 4 is a transverse vertical section through the machine.

Fig. 5 is a section through the construction illustrated in Fig. 6, the plane of the section being substantially at right angles to that in Fig. 6, and,

Fig. 6 is a fragmentary enlarged transverse vertical section through the motor mountings used on the machine.

Like reference characters refer to like parts in the different figures of the drawings.

In the construction of the machine a lower supporting frame is provided having spaced apart vertical sides 1 connected by vertical ends 2 which, at their upper edges, are formed with horizontal guides 3 on which the major

portion of the mechanism is mounted for lateral reciprocatory movements between the sides of the machine. To each side 1 of the frame a plurality of spaced apart vertical brackets 4 are rigidly connected, serving to support a longitudinal horizontal table 5 at each side of the machine which in turn supports a jig 6 resting above and on each table. With the form of work as illustrated in Fig. 1 the jig is an elongated member having a concave upper side shaped that the work may fit thereagainst. A plurality of spaced apart brackets 7 are attached to the outer side of each jig 6 and are curved upwardly and over the same, carrying screw clamps 8 by means of which the work, namely, the wood bars 9, may be securely yet releasably clamped to the upper sides of the jigs.

Above the lower frame of the machine is a horizontal rectangular frame 10 of metal having spaced apart sides connected by cross members 11 which extend below the sides of the frame and are shaped to engage with the guides 3 on the ends 2 of the lower frame. A drive shaft 12 extends between said sides 2 and is driven at low speed from a motor 13, suitable reduction gearing being housed within the housing 14 between the motor and the shaft. A second shaft 15 is mounted above the drive shaft 12 and is driven therefrom through interposed gears 16. At one end of the shaft is a disk 17, diametrically slotted with a T-slot 17^a for the adjustable connection of a link 18 at one end in said slot which at its other end connects to an arm or bracket 19 extending downwardly from the frame 10. It is evident that in the operation of the machine said frame 10 is movable laterally back and forth on the sides 2 of the lower supporting frame and that the extent of movement is governed by the connection of one end of the link 18 to the disk 17, having a greater range of movement the farther out the end of the link 18 is from the center of the disk 17.

Each of the sides of the laterally movable frame 10 has a T-slot 20 cut lengthwise thereof in its upper side. A plurality of supports, one for each of the mortising units of the machine, are located across and between

said sides of frame 10, each having combined guides and brackets 21 at their sides connected by a rack member 22, and the same are adjustably mounted on said sides 10 by T-bolts 23 passing through the brackets 21 and having their heads located in the slots 20, whereby said supports may be adjusted to various positions in the length of the sides of the laterally movable frame. On each of the supports described a vertically adjustable member 24 is mounted for vertical adjustment between the guides 21 and at one side of the back 22. Each of said members 24 at its upper side and at each end carries an upwardly projecting side ear 25. A lug 26 extends horizontally from the member 24 thru a slotted opening in the back 22 (see Fig. 5) and an adjusting screw 27 is mounted on said back 22 and threads through the lug 26, whereby any member 22 and the mortising device carried thereby, as will later appear, may be vertically adjusted to different positions.

Between the ears 25 of each of said members 24 a table 28 is located, formed at its upper side with spaced apart dovetailed horizontal guides 29 which are located at right angles to the length of the table 28. At each end and at the lower portion of the table 30 downwardly extending ears 30 are provided which lie against the inner sides of the ears 25. A pin and slot connection, such as indicated at 31, is made between the ears 30 and 25 whereby the table 28 may be adjusted about the axis of shaft 32 which passes through said ears 25 and the ends of the table and provides an adjustable mounting for the table on said ears. The pins which pass through the slots in said pin and slot connection 31 are set screws which are tightened to hold the table in any position to which it has been adjusted.

An electric motor 33 is located above and movably mounted on the guides 29 of the table 28, the motor housing being formed at its lower side with cooperating guides 29^a (see Fig. 6) one of which is a gib, loosened and tightened by means of set screws 29^b whereby the motors of one or more units, in certain operations of the machine, may be secured against movement with respect to their tables 28 on which they are slidably mounted. The motor is located so that its shaft is parallel to the length of the table 28 and transverse of guides 29. The motor shaft 34 extends beyond each end of the motor housing and at each end is designed to carry a mortising tool 35, as shown in Fig. 4.

On the under side of the motor housing and transverse to the length thereof a rack 36 is located which meshes with a pinion 37 mounted on the shaft 32. It is, of course, understood that in the length of the machine several of the mortising units with the electric motors 33 are mounted and each is in-

dependently adjustable to different positions. The shafts 32 all extend toward one side of the machine, as indicated in Fig. 4. To the side of the laterally movable frame 10 described over which said shafts extend, spaced apart guides 38, (see Fig. 3) are attached in which an elongated bar 39 is slidably mounted for reciprocatory movements. At each side of the bar a T-slot 40 is cut. An arm 41 is secured to the outer end of each of the shafts 32, is longitudinally slotted at its free end for a distance and is adjustably connected to one end of a link 42, the opposite end of which has an adjustable connection with the reciprocating bar 39 through suitable T-bolts 43 received in the T-slots 40, alternate links 42 being connected at opposite sides of bar 39.

An electric motor 43 is carried between the sides of the laterally movable frame 10 and through a suitable connecting shaft 44, drives a disk 45 diametrically slotted as shown at 45^a, for the adjustable connection of a crank arm 46 therewith at one end, the opposite end having pivotal connection to the adjacent end of the reciprocating bar 39. It is evident that when the motor 43 is operating the bar 39 is reciprocated and the length of stroke thereof is dependent upon the distance that the end of the crank arm 46 is adjusted from the center of the disk 45; and the stroke can be varied and made of greater or less length as desired. The electric motor 43 has associated therewith the usual electrical control devices housed within a housing or control box 47, which specifically form no part of the present invention, and in practice cables 48 connect the controls with the motor 13, previously described.

Operation: The bars 9 located on the jigs 6 and clamped thereto, as described, are disposed so that the mortise tools 35 may engage therewith at their inner sides to cut the mortises 49. It is evident, of course, that for different thicknesses of work or the like, or if the mortises are to be placed closer to either the upper or lower sides of the work, by operating the adjusting screws 27 each of the mortising tools may be adjusted to desired positions; and as such adjustment of each motor in a vertical direction is independent of the other the mortises may be formed in the side edges of the bars 9 at any desired levels.

With the motors 13 and 43 running and, of course, the mortising motors 33 also operating, there is a continuous back and forth lateral movement of the lower frame 10 on the ends 2 of the stationary supporting frame. This movement carries the mortising tools 35 on the machine toward one of the bars 9, for instance, the one at the left shown in Fig. 4. The reciprocating bar 39 is moved back and forth and as a result, due to the connection of links 42 with the arms 41, the shafts 32 are rocked with a consequent reciprocatory movement of each motor 33 in a

direction transverse to its length. This movement occurs simultaneously with the lateral movement of the frame 10 thereby carrying the mortising tools 35 back and forth rapidly as the same are fed into the work, causing a simultaneous cutting of the mortises 49. By reason of the various independent adjustments of the mortising units whereby the same may be tilted to different angles to the vertical, as best shown in Fig. 3, combined with the ability to vertically adjust each one independently, it is possible to cut the mortises in the curved bar 9 so that the mortises from one end of the bar to the other are located in an arc similar to the arc of curvature of the work. It is further evident that by disconnecting any link 42 from the bar 39 and tightening the gib 29^a, used with the mortising machine which is thus disconnected from the bar 39, such mortising unit will not cut a long mortise but will merely bore a hole in the side of the work 9. It is further evident that the adjustable connection of the links 42 with the arms 41 make it possible to individually set each unit for a desired length of mortise and the mortises do not all have to be of the same length merely because the bar 39 has the fixed reciprocatory movements. The depths of the mortises may also be controlled by the connection of link 18 to the disk 17.

In fact, with this machine it is possible to cut practically any and all desired mortises in the side of a piece of work, alining them or placing them on a curve, or locating them in different vertical planes, making them of the same or different lengths, and boring straight holes with any one or more of the mortising units without cutting a long mortise. And, of course, by using different jigs 6 at the sides of the machine different shapes of work may be taken care of thereon.

The lateral reciprocatory movement of the frame 10 takes the mortising tools 35 first into engagement with one of the bars 9 to cut the mortises 49 therein and afterward moves the mortising units so as to bring the tools 35 at their opposite side into engagement with the other bar 9. A man located at each side of the machine takes care of the work, removing that which has been finished during the period that the work is being done on the bar 9 at the opposite side of the machine and clamping a new bar in place before the movement of the frame 10 carries the mortising tools 35 at his side of the machine back to working position. The movement of the frame 10 is relatively slow. The depth of the mortises cut is controlled by the extent of the movement of the frame 10 which is controlled through the adjustable connection of the link 8 to the disk 17.

Although this machine has been shown and described with its parts in a horizontal plane and other members in other planes, it is to

be understood that such an arrangement is not essential and that the device can be readily made and operated with its members in other planes than those shown and described. Therefore, the specification of the arrangement of the parts in certain planes is to be understood as having only a relative meaning.

From the foregoing it is apparent that we have invented a very practical universal mortising machine. The many types of work which can be done with the machine have been fully outlined. In practice the machine has proved exceptionally satisfactory for quantity low cost production work. The invention is defined in the appended claims and is to be considered comprehensive of all forms of structure coming within their scope.

We claim:

1. A mortising machine comprising, a mortising unit including a horizontal shaft to the end of which a mortising tool is adapted to be secured, a table on which the unit is mounted for reciprocation in a direction transverse to the length of the shaft, a horizontal rock shaft on which the table is mounted for tilting adjustments, rack and pinion connections between the unit and said shaft, means for rocking said shaft, a support for said table, and means for angularly adjusting the table with respect to the support about the axis of the rock shaft.

2. In a mortising machine, a mortising unit including a vertical guide, a supporting member vertically adjustable on said guide, a rock shaft carried at the upper end of the guide, a table tiltably mounted on the rock shaft, a shaft carrier slidably mounted at the upper side of the table for movement transverse to the rock shaft, rack and gear connections between the shaft carrier and the rock shaft for reciprocating said shaft carrier when the shaft is rocked, a mortising tool shaft for said shaft carrier projecting to one side thereof, and a mortising tool secured to and projecting from an end of said shaft.

3. A construction containing the elements in combination defined in claim 2, combined with a horizontal bar mounted for reciprocation at one side of the mortising unit, means for reciprocating said bar, and connections between the rock shaft and bar for rocking the shaft from said bar.

4. In a mortising machine, a horizontal frame, a plurality of spaced apart vertical guides on said frame, a support mounted for vertical adjustment on each of said guides, a horizontal rock shaft carried at the upper end of said support, a table tiltably mounted on said shaft and adjustable to different positions thereon, a shaft carrier slidably mounted at the upper side of the table for movements transverse to the rock shaft, a mortising tool shaft on said shaft carrier, a mortising tool connected to and extending from one

end of the shaft, rack and gear connections between the rock shaft and shaft carrier, a horizontal bar mounted for reciprocation at one side of all the mortising units, connections between the rock shafts and said bar for rocking all of said shafts on reciprocation of the bar, and means for reciprocating said bar.

5. A mortising machine comprising a support, a horizontal frame mounted on said support for movements back and forth transverse of the length thereof, means for moving said frame back and forth on its support, a plurality of mortising units mounted at spaced apart points on the frame, means for individually adjusting said units vertically, each of said units including a shaft and a mortising tool connected to and projecting from the shaft, means for individually tilting said units to different positions about horizontal axes parallel to said shafts and located below the same, and means for mounting said units for back and forth movements in directions parallel to the length of said frame.

6. In a mortising machine, a mortising unit comprising, a vertical guide, a vertical support adjustably mounted on said guide, a horizontal rock shaft mounted at the upper end of the support, a table mounted on said rock shaft for tilting movement, means to secure the table in any position with respect to the support to which it is tilted, a shaft carrier having a mortising tool shaft and slidably mounted at the upper end of the table for movements transverse to the axis of its shaft, a rack and gear connections between the shaft carrier and the rock shaft, an arm connected to one end of the rock shaft, a horizontally reciprocable bar mounted alongside of said vertical guide, means for reciprocating the bar and a link connection between said bar and the end of said arm.

7. A mortising machine comprising, a support, an elongated frame slidably mounted on said support for reciprocating movements transverse of the length of the support, a plurality of vertical guides mounted on and extending transversely of the frame, means for adjustably securing said guides to the frame whereby the same may be moved to different positions in the length thereof, vertical supports adjustably mounted on said guides and adjustable to different heights, a horizontal rock shaft mounted at the upper end of each vertical support, a table tiltably mounted on each rock shaft, means for securing each table at any position to which it may be tilted with respect to its vertical support, a shaft carrier having a mortising tool shaft and slidably mounted on and above each table for movement in a direction transverse to the length thereof, a rack at the under side of the shaft carrier, a gear on the rock shaft meshing with said rack, an arm secured to and extending downwardly from an end of each rock shaft, a bar slidably mounted on said frame

lengthwise thereof at one side of all of said vertical guides, means for reciprocating the bar, and links, one for each arm, releasably and adjustably connected to said reciprocating bar at one end and to said arms at their other ends.

8. In a mortising machine, a vertical guide, a vertical support mounted for vertical adjustment thereon, means for adjusting the support vertically, a horizontal rock shaft mounted across the upper end of the support, a table tiltably mounted on the rock shaft, means for securing the table in any position to which it may be tilted, a shaft carrier and shaft located lengthwise of and above the table and slidably mounted thereon for reciprocatory movements transverse of the length of the table, a rack on the under side of the shaft carrier, a pinion on the rock shaft meshing therewith, an arm connected to an end of the rock shaft, said arm having a longitudinal slot adjacent its free end, a link adjustably connected at one end to the slotted end of the arm, a reciprocating bar, means to reciprocate the same, releasable connections for securing the other end of said link to the bar and a mortising tool connected with and projecting outwardly from the end of the shaft of the shaft carrier.

9. In a mortising machine, a support, a horizontal elongated frame mounted for reciprocatory movements on said support in a direction transverse to its length, a plurality of mortising units carried above and transverse of the frame in spaced apart relation thereon, means for adjusting said units individually to different positions in the length of the frame, means for reciprocating the frame on its support, means for adjusting the extent of reciprocatory movement of said frame, a shaft carrier at the upper end of each mortising unit having a spindle shaft located transversely of the length of said frame, means for adjusting each shaft carrier vertically to different positions, means for adjustably tilting each shaft carrier about a horizontal axis, said axis being transverse of the length of the frame, means for mounting said shaft carrier for reciprocatory movements in a direction parallel to the length of said frame, a mortising tool connected with and extending from an end of the spindle shaft, an operating bar located along one side of all of the mortising units, releasable connections between the same and said shaft carriers for reciprocating all of selected ones of said shaft carriers simultaneously, and adjustable means included in said connections for individually varying the extent of the reciprocatory movements of the shaft carriers.

10. A mortising machine comprising, a support, a horizontal frame mounted for reciprocating on said support in a direction transverse to the length thereof, a work hold-

ing device located at a longitudinal side of the machine, a plurality of mortising units mounted on said frame, means for individually adjusting said units in both horizontal and vertical directions, a mortising tool shaft mounted for reciprocation in a direction transverse to its axis on each respective unit and extending toward said work holding device, means for individually tilting each of said units to adjust the plane in which its respective mortising tool shaft reciprocates, a common actuating means for reciprocating all of said mortising tool shafts and individual means for adjustably connecting each mortising tool shaft with said common actuating means.

11. A mortising machine comprising, a support, a work holder mounted on said support, a frame mounted for reciprocation on said support in a direction toward and away from said work holder, a plurality of mortising units mounted on said frame for individual adjustment toward or from each other, a mortising tool shaft mounted for reciprocation in a direction transverse to its axis on each respective unit, said shafts extending toward said work holder, actuating means carried by said frame and reciprocal therewith for reciprocating all of said mortising tool shafts and individual connecting means for adjustably connecting each of said mortising tool shafts with said actuating means.

12. A mortising machine comprising, a support, a work holder mounted on said support, a frame mounted for reciprocation on said support in a direction toward and away from said work holder, a plurality of mortising units mounted on said frame for individual adjustment toward or from each other, a mortising tool shaft mounted for reciprocation in a direction transverse to its axis on each respective unit, said shafts extending toward said work holder, actuating means carried by said frame and reciprocal therewith for reciprocating all of said mortising tool shafts and individual connecting means between the respective mortising tool shafts and said actuating means, said connecting means being adjustably connected to said actuating means whereby the adjusted position of its respective unit is accommodated.

13. A mortising machine comprising, a support, a work holder mounted on said support, a frame mounted for reciprocation on said support in a direction toward and away from said work holder, a plurality of mortising units mounted on said frame for individual adjustment toward or from each other, a mortising tool shaft mounted for reciprocation in a direction transverse to its axis on each respective unit, said shafts extending toward said work holder, actuating means carried by said frame and reciprocal therewith for reciprocating all of said mortising tool shafts and individual connecting means

between the respective mortising tool shafts and said actuating means, each connecting means being adjustably connected to a respective mortising tool shaft to vary the reciprocation of said shaft relative to the reciprocation of said actuating means.

14. A mortising machine comprising, a support, a work holder mounted on said support, a frame mounted for reciprocation on said support in a direction toward and away from said work holder, a plurality of mortising units mounted on said frame for individual adjustment toward or from each other, a mortising tool shaft mounted for reciprocation in a direction transverse to its axis on each respective unit, said shafts extending toward said work holder, actuating means carried by said frame and reciprocal therewith for reciprocating all of said mortising tool shafts and individual connecting means between the respective mortising tool shafts and said actuating means, each connecting means being adjustably connected to a respective mortising tool shaft to vary the reciprocation of said shaft relative to the reciprocation of said actuating means, and each connecting means also being adjustably connected to said actuating means whereby the adjusted position of its respective unit is accommodated.

15. A mortising machine comprising, a plurality of spaced apart substantially vertically positioned mortising units, each including a horizontal shaft and a mortising tool connected to and projecting from an end of the shaft, means for adjusting each unit individually in a vertical direction, means for tilting each unit individually about a horizontal axis parallel to its shaft, means for slidably mounting each unit for movements in directions transverse to the axis of the shaft, a single operating means for moving all of said units, means for reciprocating said operating means, releasable connections between said operating means and said units for slidably reciprocating the same, all of said mortising units being mounted in spaced apart relation on a horizontal frame, and said operating means being also mounted on said frame, a support for said frame on which the same is mounted for sliding movements in a direction at right angles to the sliding movements of said units, and means for reciprocating said frame on its support simultaneously with the operation of said units.

In testimony whereof we affix our signatures.
